UNITED STATES PATENT OFFICE

2,660,429

APPARATUS FOR AUTOMATICALLY
CENTERING MOVING OBJECTSEdwin T. Lorig, Pittsburgh, Pa., assignor to
United States Steel Corporation, a corpora-
tion of New Jersey

Application June 4, 1951, Serial No. 229,723

9 Claims. (Cl. 271—2.6)

1

This invention relates to apparatus for automatically centering a moving object such as a strip and is a continuation-in-part of my copending application, Serial No. 145,648, filed February 23, 1950, now Patent No. 2,593,158. The apparatus disclosed in said patent has proved to be entirely satisfactory for most purposes, but there are certain applications where centering action faster than that obtained by that apparatus is required.

It is therefore an object of my invention to provide apparatus for automatically and rapidly centering a moving object.

This and other objects will be more apparent after referring to the following specification and attached drawings, in which:

Figure 1 is a sectional view of one embodiment of my invention;

Figure 2 is a sectional view, similar to Figure 1, but showing a load being applied to the device;

Figures 3 and 4 are fragmentary views showing slight modifications of my device; and

Figure 5 is a sectional view, similar to Figure 1 showing a further embodiment of my invention.

Referring more particularly to the drawings the reference numeral 2 indicates a rotatable shaft mounted in bearings 4. The shaft 2 may be either idle or driven, in which latter case an extension 6 is provided at one end for connection to a driving mechanism (not shown). A pair of opposed frusto-conical rolls 8 are mounted on the shaft with their large diameter ends adjacent each other. Each of the rolls 8 consists of a tube 10 surrounding the shaft 2 and fastened thereto adjacent the bearing 4 by means of an end ring 12. The internal diameter of the tube 10 is greater than the outside diameter of the shaft 2 so that its unsupported end is free to deflect under load. A thin end web 14 is fastened to the tube 10 adjacent its outer or supported end and a similar web 16 fastened to the tube 10 adjacent its inner or free end. A frusto-conical rim portion 18 is fastened to the spaced apart webs 14 and 16. The web 16 may be positioned on the tube 10 at any point between the position shown and the web 14. While both webs are shown fastened to both the tube 10 and rim portion 18, part of these connections may be omitted, it only being necessary that the rim portion 18 be centered on the tube 10 and rotate therewith. When pressure is applied to the surface of the rolls 8 by means of a strip S the rotating rims 18 and tubes 10 move inwardly toward the shaft 2 at the line or surface of contact and outwardly at a point diametrically opposite as shown in Figure 2. The

2

strip S may have either line contact with the rims 18 or be wrapped around an arc thereof. As long as the strip S is centered on the rolls 8 and the bearing pressure of the strip on the rolls is uniform over its full width, no lateral movement of the strip will occur as it passes over the roll. If the strip is off-center or the strip contact is non-uniform from side to side, the forces exerted by the roll having the greatest contact with the strip S will cause the strip to move rapidly into a centered position on the rolls.

A slight modification of my device is shown in Figure 3 in which a tongue and groove construction 20 is provided at the center of the rims 18 in order to cause both rims to deflect in unison.

Figure 4 shows another slight embodiment of my invention in which a rubber or neoprene gasket 22 is provided between the center webs 16 to seal the assembly and prevent infiltration of injurious materials into the interior thereof.

Figure 5 shows another embodiment of my invention in which the frusto-conical rim portion 18 is omitted. In this embodiment a plurality of spaced apart webs 24 are fastened to each of the tubes 10 with the frusto-conical rims of each of the rolls being provided by the outer surface of the webs. The operation of this embodiment is the same as that of Figure 1.

While several embodiments of my invention have been shown and described it will be apparent that other adaptations and modifications may be made without departing from the scope of the following claims.

I claim:

1. Apparatus for automatically centering a moving object comprising a rotatable shaft, a pair of axially opposed rolls mounted on said shaft substantially coaxial therewith, each of said rolls including a tube surrounding said shaft, the internal diameter of said tube being substantially greater than the outside diameter of said shaft, the outer end of said tube being fastened to said shaft coaxially therewith and its inner end being unsupported and the tube being free to deflect under load in a direction transverse to its axis about its shaft attached end as a pivot, a plurality of spaced apart webs surrounding said tube for rotation therewith, a rim portion carried by said webs substantially coaxial with said shaft, the first of said webs being adjacent the outer end of said rim portion and the second of said webs being between the first web and the inner end of the rim portions.
2. Apparatus for automatically centering a moving object comprising a rotatable shaft, a

pair of axially opposed frusto-conical rolls mounted on said shaft substantially coaxial therewith with their large diameter ends adjacent each other, each of said rolls including a tube surrounding said shaft, the internal diameter of said tube being substantially greater than the outside diameter of said shaft, the outer end of said tube being fastened to said shaft coaxially therewith and its inner end being unsupported and the tube being free to deflect under load in a direction transverse to its axis about its shaft attached end as a pivot, at least two spaced apart webs fastened to and surrounding said tube one adjacent the inner end thereof and the other spaced outwardly therefrom, and a rim portion carried by said webs and extending therebetween substantially coaxial with said shaft.

3. Apparatus for automatically centering a moving object comprising a pair of opposed rotatable rolls, each of said rolls including a central tube supported at its outer end, the axes of said tubes being substantially in alignment, the inner end of said tube being unsupported, and the tube being free to deflect under load in a direction transverse to its axis about its outer end as a pivot, a plurality of spaced apart webs surrounding said tube for rotation therewith, a rim portion carried by said webs, substantially coaxial with said tube, the first of said webs being adjacent the outer end of said rim portion and the second of said webs being between the first web and the inner end of the rim portion, and means for positively rotating the rolls in unison.

4. Apparatus for automatically centering a moving object comprising a pair of opposed rotatable frusto-conical rolls arranged with their large diameter ends adjacent each other, each of said rolls including a central tube supported at its outer end, the axes of said tubes being substantially in alignment, the inner end of said tube being unsupported and the tube being free to deflect under load in a direction transverse to its axis about its outer end as a pivot, at least two spaced apart webs fastened to and surrounding said tube one adjacent the inner end thereof and the other spaced outwardly therefrom, a rim portion carried by said webs and extending therebetween substantially coaxial with said tube, and means for positively rotating the rolls in unison.

5. Apparatus for automatically centering a moving object comprising a rotatable shaft, a pair of like axially opposed rolls mounted on said shaft substantially coaxial therewith, each of said rolls including a tube surrounding said shaft, the internal diameter of said tube being substantially greater than the outside diameter of said shaft, the outer end of said tube being fastened to said shaft coaxially therewith and its inner end being unsupported and the tube being free to deflect under load in a direction transverse to its axis about its shaft attached end as a pivot, and a plurality of spaced apart circular webs surrounding said tube for rotation therewith, said webs increasing in diameter toward the inner end of said tube, the peripheries of said webs lying within a frusto-conical surface coaxial with said tube.

6. Apparatus for automatically centering a moving object comprising a rotatable shaft, a pair of like axially opposed frusto-conical rolls mounted on said shaft substantially coaxial therewith with their large diameter ends ad-

5 jacent each other, each of said rolls including a tube surrounding said shaft, the internal diameter of said tube being substantially greater than the outside diameter of said shaft, the outer end of said tube being fastened to said shaft coaxially therewith and its inner end being unsupported and the tube being free to deflect under load in a direction transverse to its axis about its shaft attached end as a pivot, and at least 10 two spaced apart circular webs fastened to and surrounding said tube one adjacent the inner end thereof and the other spaced outwardly therefrom, said webs increasing in diameter toward the inner end of said tube, the peripheries of said webs lying within a frusto-conical surface coaxial with said tube.

7. Apparatus for automatically centering a moving object comprising a pair of like axially opposed rotatable rolls, each of said rolls including a central tube supported at its outer end, the axes of said tubes being substantially in alignment, the inner end of said tube being unsupported and the tube being free to deflect under load in a direction transverse to its axis about its outer end as a pivot, a plurality of spaced apart circular webs surrounding said tube for rotation therewith, said webs increasing in diameter toward the inner end of said tube, the peripheries of said webs lying within a frusto-conical surface coaxial with said tube, and means for positively rotating the rolls in unison.

8. Apparatus for automatically centering a moving object comprising a pair of like axially opposed rotatable frusto-conical rolls arranged with their large diameter ends adjacent each other, each of said rolls including a central tube supported at its outer end, the axes of said tubes being substantially in alignment, the inner end of said tube being unsupported, and the tube being free to deflect under load in a direction transverse to its axis about its outer end as a pivot, at least two spaced apart webs fastened to and surrounding said tube one adjacent the inner end thereof and the other spaced outwardly therefrom, said webs increasing in diameter toward the inner end of said tube, the peripheries of said webs lying within a frusto-conical surface coaxial with said tube, and means for positively rotating the rolls in unison.

9. Apparatus for automatically centering a moving object comprising a rotatable shaft, a pair of like axially opposed rolls mounted on said shaft substantially coaxial therewith, each of said rolls including a tube surrounding said shaft, the internal diameter of said tube being substantially greater than the outside diameter of said shaft, the outer end of said tube being fastened to said shaft coaxially therewith and its inner end being unsupported and the tube being free to deflect under load in a direction transverse to its axis about its shaft attached end as a pivot, and a frusto-conical rim portion surrounding said tube and fastened thereto for rotation therewith, said rim portion being substantially coaxial with said shaft and increasing in diameter toward the inner end of said tube.
